UNITED STATES PATENT OFFICE.

THOMAS B. FITZPATRICK, OF NEWTON, MASSACHUSETTS.

DESIGN FOR A WAIST.

SPECIFICATION forming part of Design No. 25,246, dated March 10, 1896.

Application filed July 8, 1895. Serial No. 555,327. Term of patent 14 years.

To all whom it may concern:

Be it known that I, THOMAS B. FITZPATRICK, a citizen of the United States, residing at Newton, in the county of Middlesex and State of Massachusetts, have invented and produced a new and original Design for Children's Waists, of which the following is a specification, reference being had to the accompanying drawings, forming a part thereof.

10 Figure 1 is a view in perspective of my design, and Fig. 2 is also a view in perspective thereof from a different point.

My design comprises the representation of an hour-glass figure with a downward-extending intermediate section upon a background of a knitted or woven character. The hour-glass effect is obtained by the sections A A', which cross each other, and between these

crossed sections and extending from the meeting-point of the sections A A' is the intermediate section A². These sections are mounted upon the base or body B. At each end of the body or space containing this hour-glass or cross effect there is a border A² A³, which makes a side finish or frame for the intermediate design.

Having thus fully described my invention, I claim and desire to secure by Letters Patent of the United States—

The design for a waist herein shown and described.

THOMAS B. FITZPATRICK.
